No. 1,316

Des. 1316

Walter W. Standard, of Buffalo, N.Y.
Assignor to
J. S. Jewett and F. H. Root
Letters Patent No 1316 Dated Sept. 25, 1860,

The schedule referred to in these Letters Patent and making part of the same.

In all where it may concern;

Be it Known that I, Walter W. Standard, of the City of

Buffalo, County of Erie, and State of New York, assignor to Sherman S. Jewett & Francis H. Root of Buffalo aforesaid, have invented or produced a certain new and original ornamental design for Cooking Stoves, and I do hereby declare that the following is a full, clear, and exact description thereof, reference being had to the accompanying photographic drawings, and the letters of reference marked thereon.

Fig: I, represents the front plate of the stove. —

Fig: II represents one of the side plates of the stove.

Fig: III, represents one of the end plates of the elevated oven.

Fig: IV, represents one of the side plates of the elevated oven.

The front plate (Fig: I) has two sliding doors (a, a) with raised panels (b), their upper corners rounded, having alternate embossed concave and convex flutings (c) contracted to the middle of the lower edge, and expanding toward the top and sides as represented.

At the lower corners, are embossed internal scrolls (d) terminating in beads. Over these panels, and near the top of the doors, are embossed horizontal bands (e) with vertical corrugations. The panels of the jambs on either side of the sliding doors have vertical flutings (f).

In (Fig: II) (g) is a door which opens into the fire chamber, its upper corners being rounded. It has an ornament (h) at the middle of its lower edge, from which the embossed corrugations (i) spread out to the top and sides as represented. The lower edge of the plates extending back from the fire chamber is curved, and has tangential embossed corrugations (j) as represented. The opposite side plate is the same in all respects as the one just described, except that the door (g) is made a stationary panel.

In Fig: III (j) is a door which opens into the oven. It is surrounded by plain mouldings, and its upper corners are rounded. It has an embossed seashell (k) at its centre, and is surrounded by embossed scrolls and leaves (l) as represented. The edge of the plate is surrounded by a moulding (m) with concave undulations and scalloped edges. The opposite end plate is the same in all respects, except that the door (j) is made a stationary panel.

In Fig: IV, (n) is an ovate shield like emboss with a band of small beads (o) at its base (p) are convex corrugations with concave flutings between, radiating from the central emboss (n) and terminating in a border (q) of embossed

scrolls with adhering leaves as represented. r. are detached embossed scrolls at the corners. The edges of the plate have similar mouldings with concave denticulations, and scalloped edges to the end plate Fig: III. The opposite side plate is the same in all respects to the one just described.

What I claim and desire to secure by letters patent, is the a-
mental design for a Cooking Stove herein described and represented in the ac-
companying photographic drawings.
